UNITED STATES PATENT OFFICE.

HENRY C. BARKER, OF SEDALIA, MISSOURI.

BRICK-MACHINE.

SPECIFICATION forming part of Letters Patent No. 239,917, dated April 12, 1881.

Application filed February 19, 1881. (No model.)

To all whom it may concern:

Be it known that I, HENRY C. BARKER, a citizen of the United States, residing at Sedalia, in the county of Pettis and State of Missouri, have invented certain new and useful Improvements in Brick-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, in which—

15 Figure 1 is a perspective view of my improved brick-machine; and Figs. 2 and 3 are sectional elevations, with certain portions removed, of the same.

This invention appertains to improvements 20 in brick-machines; and it consists of the combination and arrangement of certain devices, substantially as hereinafter more fully set forth.

Referring to the accompanying drawings, 25 E E indicate an upright frame planted in a suitable support or base, D, and suitably braced thereto by the inclined braces F F. Across two of these braces is supported the shaft L of the wheel H. On one side of this 30 wheel is a series of cogs or teeth, with which engages a pinion on the end of the shaft M, suitably journalized upon one side of the middle one of the braces F, and reaching into the hopper, with means for grinding the clay 35 therein. The other side of this wheel H has a guttered flange, H', with a segment removed therefrom, as from H² to H³. The flange is beveled at H², to permit the slipping off of the chain J connected to the center of the wheel 40 H, and passed around the flange and connected to the rope J' of the weight or block C, having the plungers e, to let the weight with its plungers fall and compress the clay in the molds, thus forming into shape the clay for 45 bricks. The rope J', connected to the weight C, passes over a pulley, K, hung upon the frame E.

X X are rods fastened in the frame E and to the base D, and arranged one on each side 50 of the weight. They are armed at their upper and lower ends with springs T T', the upper

ones for accelerating the force of the blow of the weight with its plungers, and the lower ones for breaking the force of the fall of the weight and its plungers in the event of the falling of the same when the molds are not properly filled with clay. The weight C is connected to and guided upon the rods by eyes which strike the springs under the above-mentioned conditions. To the weight C is connected, so as to have endwise movement, the reversing-bar N, which engages with the alternating cams f f' and f' f² f³ on opposite sides of the upright frame E, so as to cause it to alternately strike the slides e e' connected to one 60 end of the chains N' N², passed around a wheel, S, upon separate peripheries thereof, to which the other ends of said chains are connected. The wheel S has a shaft, R, provided with a series of cams, P, adapted to operate upon the bottoms b of the molds a, so as to raise and lower said bottoms to push out the molded clay. An arm, l, affixed to the shaft R, is jointed to a horizontal link, g, within a slot of which works one arm of a lever, h, 75 with its other arm connected, by a link, k, to the feeder-block B d, d being the feeder proper.

Obliquely arranged to each other, and one fastened at the front upper edge of the feeder, and the other at the lower rear edge of the 80 feeder, are two kuives, V V, to clean away any adhering particles of clay from the molds and the plungers.

An off-bearing apron can be arranged conveniently to the table A, having the molds to 85 remove the molded clay therefrom as the same is pushed out thereon by the bottoms.

It will be noticed that upon the ascent of the block with the plungers, the bar N at one end will engage with the slide e, and 90 carry it up until the bar is intercepted by the cam f', (it previously having been brought under the slide e by the cam f,) freeing it from said slide. Simultaneously the wheel S will be revolved, so as to cause the cams P to elevate the bottoms b of the molds a until the molded clay is lifted out of said molds, and so as to cause, at the same time, the arm l to move the link g, which, after sliding the length of its slot upon the lever to permit of the pushing 95 out of the mold of the molded clay before bringing the block B over the molds, will act 100

upon and cause the lever *k* to push the block *B* against, and to deliver the molded clay at one side of, the mold. During the further ascent of the plunger-block *C* the bar *N* will, by striking the cam *f*, be carried under the slide *e'*, which will elevate the latter until the bar is intercepted and shifted by the cam *f³*. This action of the slide *e'* and bar *N* will reverse the motion of the wheel *S* and its adjuncts, which will have the effect to lower the mold-bottoms and move the feeder back under the hopper, and leave the molds free to receive the plungers when the block descends.

What I claim, and desire to secure by Letters 15 Patent, is—

1. In a brick-machine, the combination, with the plunger-block *C* and rope *J J'*, passing over an elevated pulley, *K*, of the wheel *H*, having the broken-away beveled flange *H'* on one side, and a series of cogs on the other side, and the clay-grinding shaft *M*, having a pinion, substantially as and for the purpose set forth.

2. The plunger-block-operating wheel *H*, 25 having the broken-away and beveled flange on one side and a series of cogs on the other side, in combination with the clay-grinding

shaft *M*, having a pinion, substantially as and for the purpose set forth.

3. The combination, with the plunger-block 30 having eyes, of the rods *X*, having the springs *T* or *T'*, substantially as and for the purpose set forth.

4. The combination of the block having the reversing-bar *N*, upright frame having the cams 35 *f f' f² f³*, slides *e e'*, chains or equivalents *N' N²*, wheel *S*, with its shaft *R*, provided with cams *P*, and mold-bottoms *b*, substantially as and for the purpose set forth.

5. The combination, with the plunger-block 40 *C*, having the reversing-bar *N*, upright frame *E*, having the cams *f f' f² f³*, and slides *e e'*, connected, by chains or equivalents *N' N²*, to the wheel *S*, with its shaft *R*, provided with cams *P*, movable mold-bottoms *b*, of the arm *l*, 45 link *g*, slotted at one end, lever *h*, link *k*, and feed-block *B d*, substantially as and for the purpose set forth.

In testimony whereof I affix my signature in presence of two witnesses.

HENRY C. BARKER.
